ROAD ROLLER

Joseph Howard Ganley, St. Paul, Minn.

Application September 8, 1941, Serial No. 409,970

3 Claims. (Cl. 94—50)

This invention relates to rolling machines for compacting and smoothing thin layers of road surface material, and particularly to such devices utilizing a plurality of compacting wheels equipped with very yieldable, resilient tires, preferably of the pneumatic type.

At the present time several makes of road rollers are utilized on highway work, such devices employing usually two series of large rubber-tired compacting wheels, the individual wheels of both series being spaced laterally apart and the second series of wheels on the rear axle of the device being substantially aligned with the spaces between the wheels of the first series so that most of the area over which the machine is drawn will be compacted by the cumulative action of the several wheels. The use of pneumatic or compressible rubber tires overcame, to a large extent, the sticking of road materials containing all bitumen, tar, etc., and distinctly improved compaction, as contrasted with hard rollers. Such devices have been weighted with sand bags, rock or other heavy material and have been fairly successful in making and repairing roads.

However, the said road rollers heretofore used have, because of the alignment of the rear wheels with the spaces between the front series of wheels, disturbed the successively compacted areas, producing lateral pressures and shear which left the stratum ununiformly compacted and more or less corrugated.

Several successive rollings with such devices are usually required, and even then efficient and uniform compaction of the road area cannot be obtained. Furthermore, such prior devices have had a relatively high center of gravity when weighted, have employed many compacting wheels (often from nine to eleven), have been, in spite of such a large number of wheels operative on a comparatively narrow width of roadway, and because of the high center of gravity and narrow width have not been capable of use on the road shoulders.

It is an object of my invention to provide a comparatively simple, highly efficient machine for uniformly compacting and smoothing a layer of road surface material which in one operation will complete the compacting and smoothing of a relatively wide area of road surface, thereby eliminating a substantial percentage of the time and labor heretofore required.

A further object of my invention is the provision of a machine having a series of highly resilient compacting wheels constructed to cause each succeeding roll at each of the two sides of

the machine to add to the portion previously rolled, leaving one side of the material compacted loose and free to spread away from the previously rolled area and, in so doing, to provide the least possible side pressure or shear in the cumulative rolling function.

Another object is the provision of relatively wide, highly yieldable compacting tires constructed and arranged to successively act to obtain substantially only vertical pressure upon the compacted area, or, in other words, to utilize compacting tires of such diameter that the greatest amount of flat contact surface exerting downward and vertical compacting forces shall be employed, with the successive wheels staggered to cause successive areas of vertical thrust to at least abut.

A further object is the provision of a compacting and smoothing road roller having a minimum number of very resilient, wide compacting wheels arranged successively from front to rear at each side of the machine on sides of an acute angle, whereby successive outward compacting operation in the manner of a flat iron is obtained with high efficiency.

It is another object to provide a machine of the class described adapted to operate upon a relatively wide surface and having rearwardly disposed wheels spaced a wide distance apart and also having a very low center of gravity to enable the machine to efficiently work upon inclined surfaces such as a banked highway or the shoulders of a road without danger of tipping over.

A still further object is the provision in such a machine, of compacting wheels and tires constructed to permit ready removal of any one of said tires without removing any of the others.

These and other objects and advantages of my invention will be more apparent from the following description made in connection with the accompanying drawings, wherein like reference characters refer to the same parts throughout the several views, and in which:

Figure 1 is a plan view of an embodiment of my invention equipped with five compacting rollers;

Figure 2 is a side elevation of the same with a portion broken away to show the ballast or load;

Figure 3 is a rear elevation on a somewhat larger scale;

Figure 4 is a diagrammatical vertical section showing the rolling and overlap between the areas compacted by one of the front and one of the next successive rear wheels;

Figure 5 is a diagrammatical plan view showing another form of the invention with the wheels ar-

ranged somewhat differently than in the form first described, and

Figure 6 is a similar diagrammatical view of a still different form of the invention.

In the form of the invention shown in Figures 1 to 3, inclusive, I provide a substantially rigid horizontal frame comprising a pair of spaced side beams 9 secured at their forward ends by a cross beam 10 and, as shown, diverging at their rear ends to form a V-shaped rear member 11, the vertex of which is aligned with the longitudinal center line of the device. Supported on the said frame is a large weight-receiving hopper H, T-shaped in plan view, and, as shown, having its upper edges secured to the side beams 9 and extending in depth to a plane a few inches above the ground level. The tips of the T-shaped hopper extend outwardly beyond the side members 9 of the frame while the body of the hopper is disposed within the frame, as shown, and suspended therefrom.

The said frame is supported upon a series of wide, compacting wheels, each equipped with a very wide compacting tire of highly compressible resilient construction, such as a pneumatic tire. I particularly wish to emphasize the desirability of pneumatic tires of relatively very wide tread surface, preferably from 12 to 18 inches of contacting tread surface, to accomplish some of the improved functions of my invention. Wide pneumatic tires, such as are used in the landing gear of airplanes, have been highly successful and I have obtained very successful results with such airplane landing gear tires of 18-inch or 19-inch width having a tread surface contacting width of approximately 16 inches, and being of a size 45 x 20 x 10 inches, and carrying about ten pounds air pressure to the square inch, although, of course, other tires, pneumatic or compressible solid tires, may be utilized, all within the scope of my invention. It is to be understood that inflation to ten pounds per square inch is to mean such a pressure when the tires are without any load.

As shown in Figures 1 and 2, a pair of front-tired wheels 12 are utilized, mounted on a short, heavy front axle 13 which is rigidly connected by a very heavy vertical sleeve 14 with a turn-table 15. Turn-table 15 rides below a large turn-table disc 16 mounted below a heavy cross bar 17 traversing the forward portion of the frame, and suitable bearings and races (not shown) are provided between the turn-table and disc 16 to facilitate turning and steering action of the axle 13 and front wheels 12. A wide draft plate 18 is fixed to the forward portion of turn-table 15 and has secured thereto a draft bar 19 for connection with a truck or tractor to enable the machine to be drawn over the ground.

Adjacent the rear of the machine and preferably mounted transversely in the rear portion of hopper H is a heavy rear axle 19 preferably stationary, and upon which widely spaced compacting wheels 20 are mounted for preferably independent revolution. Wheels 20, as shown, are of similar size and equipped with similar tires to the front wheels 12, and are disposed in staggered relation outwardly of said front wheels in position to compact areas of road surface extending outwardly of the areas compacted by the spaced front wheels 12 and slightly overlapping the said front wheel areas, but with the flat bearing surface portions of the very wide tires or the areas compacted by vertical downward forces of the two areas abutting, as clearly shown in Figure 4. The wheels 20, it will be noted, are disposed just

rearwardly of the laterally projecting portions or tip of the weight hopper.

A fifth or rear tired wheel 21 is disposed centrally of wheels 20 normally in alignment with the longitudinal center line of the machine and, as shown, revolubly connected with an inverted yoke 22 having a thrusthead 22a which underlies a heavy bearing sleeve 23 rigidly connected with the apex of the rear V end of the vehicle frame. A heavy king bolt 22b extends from the yoke 22 through sleeve 23 to form the pivot for turning of the yoke and its connected wheel.

A short steering arm 24 is fixed to the upper end of king bolt 22b extending normally transversely of the machine and has connected to the outer end thereof an elongated steering rod 25 which diagonally crosses the longitudinal center of the vehicle frame and has its forward end connected with a short actuating arm 26 affixed to a vertical king bolt 14a which is rigidly connected with the heavy sleeve 14 which carries the front wheel axle.

The rear end of actuating arm 26 is adjustably affixed to the steering arm 24 of the rear wheel and, as shown, several bolt holes 24a are provided in arm 24 for reception of a bolt connecting member. Wheel 21 is positioned to compact the area of road surface between the areas compacted by front wheels 12 and, as shown, is of similar size and equipped with a tire similar to those of the front wheels. The horizontal bearing surface of the compacting wheel 21 is at least of a width equal to the distance between the areas compacted by the straight, downward force components by the front wheels 12, and the actual width of the tires of wheels 12 and 21 are such as to cause an overlap of the compacted areas, as clearly shown in Figure 3.

In operation of the machine described, the hopper H is loaded with sand bags, rocks, or other heavy material to the requisite weight for the particular stratum to be rolled. Loads varying from three to ten tons may be utilized. The machine is attached to a truck or other suitable traction means, and is drawn over the prepared road stratum. My device is very efficient for uniformly compacting and smoothing road surface materials for the base, wearing surface and seal coating of roads and may be successfully utilized when the materials are in moist condition before adhesion is obtained through aeration or settling of the material.

As the machine is drawn over the road surface the two front rollers, as shown in Figure 3, compact relatively wide strips, the greater part of the bearing area of the two wide tires being disposed flatwise against the surface, and the compacting forces being vertical and downward throughout a very large percentage of the tread area. Only at the rounded sides of the tires are radial and oblique downward compaction forces exerted. The next series of two wheels 20 disposed outwardly of the front wheels, compact strips of road outwardly of the first compacted areas, the compacting areas of the front wheels and wheels 20 overlapping to the point (as clearly shown in Figure 3) where all the straight line forces of the wheels compact areas at least in abutment. Thus the effect of the rounded sides of the compacting tires where the tread surfaces join the side walls is negligible since the flat compacting tread areas of the successive wheels, which exert only vertical downward thrust, abut. In the function of the machine the central part of the road treated is first compacted and then successively

outward strips are compacted, leaving always one side of the material rolled loose and free to spread away from the previously rolled area, the front wheels 12 and rearward wheels 20 functioning in compacting action in a manner similar to the principle of a flat iron.

The rear wheel 21 compacts an area or strip of road which was left unpacked between the front wheels of the device. Here again it will be noted from an inspection of Figure 3 that the width of the compacting tire on wheel 21 is such as to overlap at the side edges the compaction areas treated by the front wheels to such extent that the flat tread surface of wheel 21 exerting only vertical down thrust, compacts an area at least contiguous to and abutting the straight line force compacting areas of the front wheels.

Thus it will be seen that with the excessively large pneumatic or other highly compressible tires and the structure and arrangement of the wheels, frame and load of my machine, a very wide area of road stratum may be very efficiently and uniformly compacted in one operation of the machine.

The utilization of the flat iron principle of compacting and the substantial elimination of radial compacting forces from the actual compacted areas, prevents side pressures and shear and the tendency to undo the compaction of the previous wheels. In Figure 4 the relative overlap of the compacting of the front wheels 12 and wheels 20 is shown. Arrows indicate the compacting forces and components. It will be noted that the overlap is such that the abutting compacted strips or areas designated by the letters *x* and *y* are substantially uniformly compacted by straight line downward forces only, the effects of the rounded side edges of the bearing portions of the tires being negligible since the rearwardly disposed tire overlaps the first compacted strip to such extent that the portion of the area affected by oblique or radial compacting forces is subsequently compacted by straight line downward forces from the rearwardly disposed and outwardly staggered wheel.

It will be noted that the weight or load is suspended from the horizontal frame of the machine, the center of gravity of the device thus being maintained very low relative to the wheels. It will further be noted that the spacing of the two large wheels 20 is wide, and that, with the low center of gravity, makes it possible for my device to very successfully operate on the shoulders of a road where the shoulders are considerably inclined without danger of the machine tipping.

In the travel of the machine through a curved path, as the front wheels are turned by the draft bar, turning action is transmitted and reversed to the rear wheel 21 to cause the compacting wheels and the machine to efficiently travel over the desired path.

The hopper may be uniformly loaded to the desired weight and in the embodiment illustrated, weights up to ten tons may be successfully carried and handled by the machine with tires of the type illustrated and described.

In Figure 5 I have diagrammatically illustrated a somewhat different form of the invention where the wheels are all arranged and connected with the frame along the vertex and sides of an acute angle to provide the maximum successive outward treatment of adjacent strips of a road surface in the manner of a flat iron. Here a single forward wheel 30 is utilized preferably mounted caster-fashion for automatically turning to most

effectively and easily conform to the requirements when the machine is drawn over a curved path and the intermediate wheels 31 are preferably mounted for steering action as the wheels in the form of the invention first described. The outside outlines of the frame 32 are indicated in dotted lines. The widely spaced rear wheels 33 are related to wheels 31 as are the wheels 20 to the wheels 12 in the first form described.

In Figure 6 a slightly simpler form of the invention is shown, utilizing only four wheels arranged in the manner of the wheels 12 and 20 of the form first described. The frame 34, the outline of which is shown in dotted lines, is generally similar to the form first described, eliminating, however, the V-shaped rear end since no fifth wheel is utilized. This form of the invention functions in the precise manner of the form first described, with the exception, of course, that a space centrally of the path of the machine is left uncompacted and must be subsequently compacted by re-rolling the road surface.

From the foregoing description it will be seen that in all forms of my invention the objections to prior art devices are overcome. The successively compacted areas with my device are not disturbed through transverse or radial forces and a minimum amount of lateral pressure and shear is present in the functioning of the machine. By utilizing the very wide compacting tires with the overlapping relationship disclosed, the actual areas treated by the several wheels are compacted by straight line downward forces and the successive compacted strips are of substantially uniform compaction and lie in abutting relationship. The flat iron principle of successive compaction leaves one side of the material loose in the successive rolling and it is free to spread away from the previously rolled area, and in doing so to provide the least possible side pressure or shear in the cumulative rolling function. Thin and tapered edges of the road stratum may be successfully rolled because of structure and arrangement of my very wide compressible tires.

The tires and wheels, it will be seen, may be separately and readily removed, each independent.

With my improved structure the layer of road surface material compacted is left smooth, substantially free of longitudinal ridges which are left after initial and even subsequent rolling with the prior art machines. The width of the tires utilized, arrangement of the wheels, and specific overlapping relationship produce a highly efficient smoothing action as well as a uniform compaction upon initial rolling, and subsequent rolling is seldom needed.

In the forms of the invention utilizing more than two series of wheels, such as the form shown in Figures 1 to 3, inclusive, and the form diagrammatically shown in Figure 5, it will be seen that in traveling over an undulated road surface extending longitudinally of the path of travel, that one wheel or one set of wheels may not contact the ground at some times, in which instance greater compression is imparted through the compacting wheels to cause greater compaction of the upward undulation or bump and consequent leveling effect in an efficient manner.

It will, of course, be understood that various changes may be made in the form, details, arrangements and proportions of the parts without departing from the scope of my invention.

What is claimed is:

1. A rolling machine for compacting and

smoothing layers of road surfacing material having in combination a weight carrying frame, precisely two substantially co-axial, tire-equipped compacting wheels spaced apart a distance slightly less than the width of said tires for supporting the front of said frame, precisely two substantially co-axial, tire-equipped compacting wheels spaced apart a distance slightly less than three times the width of one of said tires for supporting the rearward portion of said frame, said second pair of wheels being disposed outwardly and laterally of said first mentioned pair in staggered relation thereto for successive compacting operation on a road surface and a fifth tire-equipped compacting wheel mounted rearwardly of said last mentioned pair of wheels and disposed substantially in alignment with the space between said first mentioned pair of wheels and connected with said frame for also serving to support the rear portion thereof, the tires of said five wheels being of similar width and compressibility whereby the successive areas of road surface compacted by downwardly directed forces will at least abut to cumulatively compact a substantially continuous road surface, said five wheels only supporting the frame and weight carried thereby.

2. The structure set forth in claim 1, and a mounting for said first mentioned pair of wheels connected to said frame for swinging action of said first pair in unison for steering purposes, a mounting for said last mentioned rear wheel connected with said frame for swinging action thereof, also for steering purposes and a steering connection between said mountings for swinging said rearmost wheel in a direction opposite to and in

unison with the swinging of said first mentioned wheels.

3. A rolling machine for compacting and smoothing layers of road surface material having in combination a weight-carrying frame, precisely a pair of resilient tire-equipped compacting wheels spaced apart a distance somewhat less than the width of said tires for supporting the front of said frame, a second pair of resilient tire-equipped compacting wheels spaced a distance slightly less than three times the width of a tire, mounted co-axially on said frame and supporting the rearward portion of said frame and having no intervening wheels therebetween, said second pair of wheels thereby being disposed outwardly and laterally of said first mentioned pair in staggered relation thereto for successive compacting operations on a road surface, and a fifth resilient tire-equipped compacting wheel mounted rearwardly of said last mentioned pair of wheels and disposed substantially in alignment with the space between said first mentioned pair of wheels, and having wide tread widths in excess of 12 inches of contactive tread surfaces whereby within the range of weights utilized for standard compacting pressures for road surfacing materials, said tires are flattened throughout a very great percentage of the tread areas in contact with the road and apply almost entirely, downward, vertical, compacting force, the spacing and arrangement of said series of wheels being such that the successive areas of the road surface compacted by only downward vertical forces will at least abut to cumulatively compact a substantially continuous road surface.

JOSEPH HOWARD GANLEY.
